US00D410087S

United States Patent

[19]

Dunshee et al.

[11] Patent Number: Des. 410,087

[45] Date of Patent: ** May 18, 1999

[54] ADHESIVE BANDAGE

[76] Inventors: **Wayne K. Dunshee; Donald G. Peterson**, both of P.O. Box 33427, St. Paul, Minn. 55133-3427

[**] Term: **14 Years**

[21] Appl. No.: **29/056,568**

[22] Filed: **Jul. 2, 1996**

[51] LOC (6) Cl. **24-04**

[52] U.S. Cl. **D24/189**

[58] Field of Search D24/189; 602/8, 602/41-56

[57] CLAIM

The ornamental design for an adhesive bandage, as shown and described.

DESCRIPTION

FIG. 1 is a perspective view of a first embodiment of an adhesive bandage showing the new design;

FIG. 2 is a top plan view of the bandage of FIG. 1;

FIG. 3 is a bottom plan view of the bandage of FIG. 1;

FIG. 4 is a right side elevational view of the bandage of FIG. 1;

FIG. 5 is a left side elevational view of the bandage of FIG. 1;

FIG. 6 is a front end elevational view of the bandage of FIG. 1;

FIG. 7 is a rear end elevational view of the bandage of FIG. 1;

FIG. 8 is a perspective view of an alternate embodiment of the invention;

FIG. 9 is a top plan view of the bandage of FIG. 8;

FIG. 10 is a bottom plan view of the bandage of FIG. 8;

FIG. 11 is a right side elevational view of the bandage of FIG. 8;

FIG. 12 is a left side elevational view of the bandage of FIG. 8;

FIG. 13 is a front end elevational view of the bandage of FIG. 8; and,

FIG. 14 is a rear end elevational view of the bandage of FIG. 8.
